UNITED STATES PATENT OFFICE.

JAMES I. WINCHELL, OF DAVENPORT, IOWA.

LOCKING DEVICE FOR AUTOMOBILES.

1,366,992.

Specification of Letters Patent. Patented Feb. 1, 1921.

Application filed November 8, 1919. Serial No. 336,683.

To all whom it may concern:

Be it known that I, JAMES I. WINCHELL, a citizen of the United States, residing at Davenport, in the county of Scott and State 5 of Iowa, have invented certain new and useful Improvements in Locking Devices for Automobiles, of which the following is a specification.

My invention has reference to locking devices for automobiles, and aims to provide a simple and efficient locking apparatus for attachment with the usual clutch-lever of the vehicle, so as to prevent the operation thereof for the purpose of starting the car. 10 It is specially adapted for use with automobiles in which the clutch-lever is forced forwardly, but can also be adapted for use in those wherein the lever moves downwardly in operating, as will be hereinafter 15 pointed out.

My invention is of a construction which enables it to be readily positioned for use, the attaching parts being so arranged and connected that they cannot be detached 20 while the device is in a locking position.

The particular construction, arrangement, and operation of the various parts of the invention will be more fully apprehended from the following specification, reference 25 being had to the drawings accompanying the same, in which:

Figure 1 is a perspective view of my invention, showing its position when in use. Fig. 2 is a plan view of the invention, detached. Fig. 3 is a side view thereof. Fig. 35 4 illustrates the shackle member by means of which the device is held in place. Fig. 5 is an edge view of the locking member, with the shackle removed. Fig. 6 is a similar plan view thereof. Fig. 7 shows the locking end of the arm 11, with a modified form thereof.

1 represents a fractional part of the foot-board of an automobile, 2 the steering-post, 45 3 the clutch-lever, and 4 the head or pedal thereof. The locking mechanism is adapted to be secured to the lower part of the steering-post by means of a shackle formed of semi-circular portions 5 and 6, hingedly 50 united as at *a*. The part 5 has a projection 7, in which is rigidly seated a bolt 8, preferably by being formed inwardly with said projection. The part 6 is provided with a perforated extension 9, adapted to 55 receive the bolt 8, which is held therein by a nut 10. The projections 7 and 9 and loops

5 and 6 are thus held in locked relation, and when said loops are inclosing the steering-post, as shown in Fig. 1, they cannot be removed except by disengaging the nut 10. 60

11 is an arm provided with a divided head 12, formed of two parts, united by a pin 13, which is irremovably held in place therein, as, for instance, by being formed integrally with said head. Said pin is 65 adapted to be held in an opening formed partly at 14 in the projection 7 and partly at 15 in the extension 9. At its opposite end the arm 11 is provided with a lock 16, which is preferably constructed as an integral part thereof, and has a hasp 17 for engagement with the lever 3 just below the tread thereof. When the parts 7 and 9 are closed, with the pin 13 in position therein, the arm 11 is held swingingly thereby, so 70 as to be permitted a limited movement at one side of said parts, as shown in Fig. 2, and in broken lines in Fig. 1.

It will be obvious that when the hasp 17 is locked about the lever 3, it will be impossible to actuate said lever, or to put into operation the mechanism for starting the car. When the owner of the car desires to use the same, he unlocks the hasp, and swings the arm to the side out of the way. 80 Said arm is held in such inoperative position by means of a spring 18, connecting such arm with the dashboard of the car at a point near the steering-post. 85

On the inner edge of the arm 11 is a ring-shaped projection 19, which incloses the nut 10 when the arm 11 is locked to the lever 3, and prevents the same from being removed or tampered with. It will be apparent, therefore, that when the arm 11 is locked to 95 the lever 3, there is no possibility of the shackle being disconnected from the steering-post, nor can the arm 11 be detached at the pivotal end thereof.

To place the device in position for use, the 100 shackle is opened, and caused to embrace the steering-post, with the hinge of said shackle in rear of the post. The head 12 is then slipped over the extension 9 until the pin 13 is seated in the recess 12, whereupon the 105 parts 7 and 9 are closed, and fastened together. The device can then be used as long as desired, without the necessity of removing the same after having been used.

In Fig. 7 is shown a modification of the 110 device, wherein the outer end of the arm 11 is provided with an upwardly projected

angle-plate 20, and a downwardly extended angle plate 21, the end of the former-plate being just beneath the pedal 4 when the arm is in a locking position, and the plate 21 being in proximity to the foot-board 1. This form is specially adapted for use with an automobile in which the clutch-lever is forced downwardly, the plates 20 and 21 preventing the downward movement thereof. 10 When the arm 11 is unlocked and turned to one side such interference is removed.

While the lock at the end of the arm 11 has been shown and referred to herein as being integral with such arm, it will be evident that it need not necessarily be, as such lock can be separately constructed, and suitably connected with the end of the arm. 15

What I claim and desire to secure, is:

1. A device of the class described, comprising a shackle, formed of two parts, hingedly united, adapted to embrace the steering post of an automobile and provided with complementary projections; means for fastening said projections together; an arm 25 swingingly mounted in said projections and provided with means for inclosing the fastening means thereof when said arm is in a locking position, to prevent release of said fastening means; and a lock on the free end 30 of said arm, adapted for engagement with the clutch-lever of an automobile, to hold the same from movement.

2. A device of the class described, comprising a shackle, formed of two parts hingedly united, adapted to embrace the steering post of an automobile and provided with complementary projections; means for fastening 35 said projections together; an arm swingingly mounted in said projections and provided with means for preventing the release of said fastening means when said arm is in a locking position; a lock on the free end of said arm, adapted for engagement with the clutch-lever of an automobile; and means for holding said arm out of locking 40 position.

3. A device of the class described, comprising a shackle, formed of two parts hingedly united, adapted to embrace the steering post of an automobile and provided with 45 projecting ends; means for fastening said ends together; a swinging member supported irremovably in said ends, and provided with means for preventing the release of said fastening means when said swinging member 50 is in a locking position; means for locking said swinging member to the clutch-lever of an automobile; and means carried by said swinging member, adapted to be interposed between the pedal of said clutch-lever and 55 the floor of the automobile.

In testimony whereof I affix my signature.

JAMES I. WINCHELL.
